Primary Examiner — Melanie Pellegrini(74) *Attorney, Agent, or Firm* — Donald J. Ranft; Collen IP(57) **CLAIM**

The ornamental design for a ring, as shown and described.

DESCRIPTION

FIG. 1 is a top right perspective view of a ring showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom left perspective view thereof.

The large gemstone shaded in grey has an appearance which contrasts with the gemstones that do not have grey shading.

1 Claim, 6 Drawing Sheets(56)
